(57) **CLAIM**

The ornamental design for a vertical take-off and landing aircraft, as shown and described.

DESCRIPTION

FIG. 1 is a front, right, top perspective view of the first embodiment of a vertical take-off and landing aircraft, showing my new design;

FIG. 2 is a rear, left, bottom perspective view thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is a front, right, top perspective view of the second embodiment of a vertical take-off and landing aircraft, showing my new design;

FIG. 10 is a rear, left, bottom perspective view thereof;

FIG. 11 is a front elevational view of the enlarged scale thereof;

FIG. 12 is a rear elevational view of the enlarged scale thereof;

FIG. 13 is a left side view of the enlarged scale thereof;

FIG. 14 is a right side view of the enlarged scale thereof;

FIG. 15 is a top plan view of the enlarged scale thereof;

FIG. 16 is a bottom plan view of the enlarged scale thereof;

FIG. 17 is a front, right, top perspective view of the third embodiment of a vertical take-off and landing aircraft, showing my new design;

FIG. 18 is a rear, left, bottom perspective view thereof;

FIG. 19 is a front elevational view of the enlarged scale thereof;

FIG. 20 is a rear elevational view of the enlarged scale thereof;

FIG. 21 is a left side view of the enlarged scale thereof;

FIG. 22 is a right side view of the enlarged scale thereof;

FIG. 23 is a top plan view of the enlarged scale thereof; and,

(Continued)

FIG. 24 is a bottom plan view of the enlarged scale thereof. The dashed broken lines in the figures are for the purposes of illustrating portions of the vertical take-off and landing aircraft and form no part of the claimed design.
